UNITED STATES PATENT OFFICE.

NATHANIEL M. LIDDELL, OF DANVILLE, ILLINOIS.

PAVING-MACHINE.

1,276,086.

Specification of Letters Patent. Patented Aug. 20, 1918.

Application filed December 1, 1917. Serial No. 204,885.

To all whom it may concern:

Be it known, that I, NATHANIEL M. LIDDELL, a citizen of the United States, residing at Danville, in the county of Vermilion and 5 State of Illinois, have invented certain new and useful Improvements in Paving-Machines, of which the following is a specification.

My invention relates to paving machines, 10 for laying bricks or blocks upon a road-bed, sidewalk or the like, while not necessarily restricted to this use.

An important object of my invention is 15 to provide a machine of the above mentioned character, which is adapted to simultaneously lay a plurality of bricks or blocks constituting a row, upon a suitable bed or foundation, in a highly expeditious and convenient manner.

20 A further object of the invention is to provide a machine of the above mentioned character, having means to propel it longitudinally along the road-bed being paved, which means are adapted to press the brick 25 or blocks into close relation.

A further object of the invention is to 30 provide a machine of the above mentioned character, the principal parts of which are operated by gravity.

35 Other objects and advantages of the invention will be apparent during the course of the following description.

In the accompanying drawings forming 40 a part of this specification and in which like numerals are employed to designate like parts throughout the same,

Figure 1 is a side elevation of a machine embodying my invention,

Fig. 2 is a plan view of the same,

45 Fig. 3 is a rear end elevation of the machine,

Fig. 4 is a longitudinal sectional view taken on line 4—4 of Fig. 2,

Fig. 5 is a detail transverse sectional view 50 through the feed conveyer, showing the same in the elevated position,

Fig. 6 is a similar view showing the conveyer lowered,

Fig. 7 is a vertical longitudinal sectional view through the means to raise and lower the feed conveyer,

Fig. 8 is a fragmentary side elevation of the feed conveyer,

Fig. 9 is a plan view of the same,

55 Fig. 10 is a transverse section taken on line 10—10 of Fig. 2,

Fig. 11 is a fragmentary plan view of the rear axle and associated elements,

Fig. 12 is a side elevation of a brake mechanism carried by the control shaft, and, 60 Fig. 13 is an edge elevation of the same.

In the drawings, wherein for the purpose of illustration is shown a preferred embodiment of my invention, the numeral 15 designates a supporting frame as a whole, comprising sides 16, and forward and rear ends 17 and 18, as shown. Arranged near the rear end 18 is an axle 19, preferably formed 65 square in cross section, to reciprocate within guide brackets 20, which are rigidly secured to the sides 16. The axle 19 carries flanged wheels 21, rotatable thereon, and adapted to travel upon side forms or curbing 22, which thus serve as a track. As more clearly shown in Fig. 11, a portion of 70 the axle 19 is provided with worm-teeth 23, to be engaged by a worm 24, rigidly secured to a rotatable shaft 25. This shaft is turned by a hand wheel 26. The shaft 25 is journaled through openings 27 in a 75 casting 28 bound upon one bracket 20'. It is obvious that means is provided to transversely shift the rear end of the frame 15, with respect to the rear axle 19. The function of this construction is to provide means 80 whereby the rear end of the machine may be arranged at an angle with respect to the curbing 22, as when laying the bricks upon a curve. As more clearly shown in Fig. 10, the forward end 17 of the frame is provided 85 with a depending support or bolster 29, which is rigidly secured thereto, and has pivotal connection, at 30, with a forward axle 31, whereby the frame is adapted to tilt in a vertical plane with relation to the 90 axle. This axle is prevented from swinging in a horizontal plane with relation to the frame by depending stops 32, which are rigidly secured to the frame, and arranged upon the rear side of the axle 31, to contact 95 therewith. The forward axle 31 carries flanged wheels 33, pivoted thereto, and adapted to travel upon the curbing 22.

The numeral 34 designates vertical standards or uprights, which are rigidly secured 100 to the sides 16 of the frame 15. The standard 34 to the left of the machine, in Fig. 2, is arranged near the rear end thereof, while the other standard 34 is disposed near the central portion of the opposite side 16, 110 whereby these standards are arranged at an angle extending transversely of the ma-

chine. The standard 34 to the right, in Fig. 2, is taller than the standard 34 to the left. Disposed inwardly of the standards 34 (see particularly Fig. 7), are slideable 5 bars 35, having elongated slots 36 formed in the upper ends thereof, to receive spaced 10 guide elements or bolts 37, carried by the standards 34. Means are provided to raise the slide bars 35, comprising cams 38, disposed beneath the lower ends thereof, to 15 contact therewith. These cams are rigidly secured to the ends of a rock-shaft 39, extending transversely of the frame 15, and having its ends journaled through the sides 20 16. As more clearly shown in Fig. 1, a hand crank 40, is rigidly secured to the rock-shaft 39, to turn it. From the foregoing description it is obvious that when the cams are turned upwardly, they will raise 25 the sliding bars 35, and when these cams are turned in an opposite direction, the sliding bars will move down by gravity. The vertically movable sliding bars 35 have a trough 41 rigidly secured to the upper ends 30 thereof. This trough extends transversely of the frame 15, at an angle with relation thereto, and is also vertically inclined, with its lower end disposed at the operating side of the machine, in proximity to the hand crank or lever 40.

The trough 41 has its upper portion provided with longitudinal vertical flanges 42 and 43, whereby such upper portion is substantially U-shaped in cross-section, and 35 adapted for the reception of a brick or the like. The flange 42 extends longitudinally throughout the entire length of the trough, while the lower portion of the flange 43 is provided with openings 44, forming spaced 40 upstanding fingers or plates 45, as more clearly shown in Figs. 8 and 9. Arranged within the trough 41 are rollers 46, carried by shafts 47. The shafts 47 are pivoted in 45 openings in the flanges 42 and 43 and in the flange 42 and the spaced fingers 45. A stop element 48 is arranged in the lower end of the trough. From the foregoing description it is obvious that I have provided a gravity 50 operated feed conveyer, for receiving the bricks, which travel longitudinally therein, to provide a row of the same.

The numeral 49 designates a supporting rod, having its ends secured to the sides 16. This rod is incapable of moving longitudinally with respect to these sides. The rod 55 49 is horizontal, and extends transversely of the frame 15 at an angle with relation thereto and is disposed in a vertical plane parallel with the vertical plane of the feed 60 conveyer. Pivoted upon the support rod 49 are arms 50 of a swinging transfer-carrier 51. These arms 50 are of different lengths and are approximately of the same length as the corresponding standards 34, but 65 somewhat shorter, to allow them to swing

under the feed conveyer. The arms 50 have apertured heads 52, which pivotally receive the rod 49, and the openings of these heads are disposed in an angle with respect to the arms, which arms 20 are arranged parallel 70 to the sides 16, when in the horizontal position, as shown in Fig. 2. The outer ends of the arms 50 are rigidly secured to a bar 53, having laterally extending arms 54, as shown more clearly in Figs. 3 and 4. The 75 arms 54 are at a right angle to the arms 50 and are adapted to be swung beneath the conveyer trough 41. Rigidly secured to the opposite ends of the arms 54 is a plate 55, disposed at a right angle thereto, and carrying spaced supporting elements or teeth 56, arranged at a right angle to the plate 55 and rigidly secured thereto. The supporting elements of teeth 56 are adapted to pass within the openings 44 and between the rollers 46, when the transverse carrier is swung to the upper position.

The numeral 57 designates a toothed quadrant, one end of which is rigidly secured to the bar 53. The opposite end of the toothed 90 quadrant is preferably formed integral with an arm 58, extending inwardly and connected with the support rod 49. The arm 58 is preferably pivoted upon the rod 49, but cannot move longitudinally with relation thereto. The toothed quadrant 57 is arranged perpendicular to the rod 49.

The toothed quadrant 57 is engaged by a gear 59 which is rigidly secured to a control shaft 60. This control shaft is journaled through stationary bearings 61, which are rigidly secured to the standards 34. The shaft 60 extends transversely of the frame, at an angle with relation thereto, and is inclined, and this shaft is disposed in horizontal and vertical planes, which are parallel to the hopper 41. The control shaft 60, as more clearly shown in Fig. 12, is provided with a brake drum 62, which is rigidly secured thereto. This brake drum 100 is arranged upon the operating side of the machine and is engaged by a brake band 63, which is thrown into and out of action by a manually operated lever 64, having latch means 65, coacting with a stationary quadrant 66. It is thus apparent that means 105 are provided to lock the control shaft against rotation. The brake drum 60 has a handle 67 rigidly secured thereto, whereby the shaft 60 may be turned.

Connected with the forward ends of the arms 50 are cables 68, extending upwardly and passed about grooved pulleys 69, pivoted to the standards 34, at 70. The cables 68 have their rear ends connected with weights 71, which are adapted to automatically swing the transfer-carrier to the upper position, when released.

I provide brick or block removing and pressing mechanism, for coöperation with 130

the transfer carrier. This mechanism comprises a transversely reciprocatory bar or head 72, disposed inwardly of and near the rear end 18. This bar is rigidly secured to 5 reciprocatory rack-bars 73 sliding within stationary guides 74. The bar 72 extends transversely of the frame 15 and is parallel with the end bar 18. The rack-bars 74 are engaged by toothed segments 75, which 10 are rigidly secured to a rock-shaft 76, extending transversely of the frame 15, and suitably journaled through the sides 16. Any suitable means may be employed to turn the rock-shaft 76, and as an illustration 15 of a means I show a lever 77, which is rigidly attached to one end of the rock-shaft 76. If desired, power operated means may be employed to turn the rock-shaft.

Rigidly secured to the transversely reciprocatory bar 72 are spaced rods or teeth 78, extending rearwardly therefrom, and operating within openings 79 formed in the end bar 18, and to be shifted rearwardly beyond this bar, across and beyond the plate 25 55, when this plate is in the lowered position, as shown in Fig. 4. The rods or teeth 78 are so positioned that they pass between the supporting elements or teeth 56, and function to push the bricks or the like 30 off of the plate 55.

The operation of the machine is as follows:

The curbing 22 for the road-bed is first laid, in the usual manner, and the machine 35 placed upon the curbing, with its flanged wheels traveling thereon as a track. At the starting end of the road-bed there is a stop or abutment against which the first row of bricks may be firmly pressed. It is customary 40 to arrange the bricks in stacks or piles, at suitable intervals along the road-bed.

The feed conveyer including the trough 41 is now moved to the raised position, by swinging the lever 40 downwardly, and temporarily retained elevated. An operator or operators now feed the individual bricks into the upper end of the trough 41, whereby they travel downwardly therein by gravity, until the lowermost brick contacts with the 50 stop 48. In this way the entire conveyer-trough 41 may be filled with a row of bricks. The transfer-carrier including the plate 55 is now moved to the upper position, as illustrated in Fig. 5, which is accomplished by 55 the operator swinging the lever 64 in the direction to release the brake band 63, whereby the weights 71 automatically swing the transfer-carrier to such upper position. The brakes are again applied to temporarily lock 60 the transfer-carrier in the upper position. While the transfer-carrier is in the upper position, the lever 40 is swung upwardly, thereby causing the conveyer-trough 41 to descend, as illustrated in Fig. 6. The supporting elements or teeth 56 of the transfer-

carrier now engage and hold the bricks, out of contact with the rollers 46, as the supporting elements are now disposed above such rollers. It is thus apparent that a row of bricks is now being held by the transfer-carrier which is adapted to swing or lower the same to and upon the road-bed. The lever 64 is suitably operated whereby the brake band 63 is sufficiently released to permit of a slow turning movement of the 70 drums 62, whereby the transfer-carrier may gradually descend to the horizontal position. If desired, a starting movement may be imparted to the transfer-carrier by an operator turning the drum 62 by means of the crank 80 67. Assuming that the transfer-carrier has been shifted to the horizontal position and locked therein by the brake mechanism, as clearly shown in Fig. 4, the row of bricks 85 will be held upon the upper surface of the plate 55. The removing and pressing mechanism is now actuated, by swinging the lever 77 forwardly, causing the bars 73 to move rearwardly. This rearward movement of the bars shifts the rods 78 rearwardly, 90 which remove the bricks from the plate 55, and deposits the same upon the road-bed, in proximity to the previously laid row, or the stop or abutment. The row of bricks thus deposited are pressed into close relation to 95 the previously laid row, by a continued rearward movement of the rods 78, and when such operation is completed, further rearward movement of the rods 78 will serve to propel or feed the entire machine forwardly, 100 a proper distance, to provide a space forwardly of the row of bricks last laid, for the reception of the next row of bricks. It is thus apparent that the mechanism which removes and presses the brick into a proper 105 close relation, also serves to propel or feed the machine longitudinally of the road-bed or curbing. The rods 78 are now shifted to the forward inactive position, as indicated in Fig. 4, whereby the transfer-carrier may 110 again be shifted to the upper position. The transfer-carrier is to be constructed in a length for receiving and transferring a row of bricks of the proper length, and the flange 43 terminates at or near one end of the 115 transfer-carrier, whereby the transfer-carrier can only pick up a row of bricks of a suitable length. As soon as the row has been picked up by the transfer-carrier, and the transfer-carrier is swinging downwardly, 120 the bricks in the upper portion of the conveyer-trough 41 begin to descend, and an operator placed near the lower end of the conveyer-trough may insert a bat in the lower end of the conveyer-trough, whereby the 125 next row of bricks will break joint with the row previously laid.

It is to be understood that the form of my invention herewith shown and described is to be taken as a preferred example of the 130

same, and that various changes in the shape, size, and arrangement of parts may be resorted to without departing from the spirit of the invention or the scope of the subjoined claims.

Having thus described my invention, I claim:

1. In a machine of the character described, a support for holding a row of 10 bricks in an elevated position, a transfer-carrier adapted to be moved to an upper position in proximity to the support and to a lower position in proximity to the road-bed, and means to effect a relative vertical 15 movement between the support and the transfer-carrier when the transfer-carrier is in the upper position.

2. In a machine of the character described, a support for holding a row of 20 bricks or the like, a transfer-carrier adapted for movement in proximity to the support, and means to effect a relative vertical movement between the support and the transfer-carrier.

25 3. In a machine of the character described, a support for holding a row of bricks or the like, a swinging transfer-carrier adapted for movement in proximity to the support, and means to lower the support 30 with respect to the transfer-carrier.

35 4. In a machine of the character described, an inclined conveyer for receiving thereon bricks or the like, a transfer-carrier adapted for movement from the inclined conveyer to the road-bed, and means to lower the inclined conveyer with respect to the transfer-carrier.

40 5. In a machine of the character described, a traveling support for receiving thereon bricks or the like, a transfer-carrier adapted for movement from the traveling support to the road-bed, and means to lower the traveling support with respect to the transfer-carrier.

45 6. In a machine of the character described, an inclined support, a plurality of spaced rollers carried thereby, a transfer carrier adapted for movement toward and away from the inclined support and having 50 spaced supporting elements to pass between the spaced rollers, and means to effect a relative vertical movement between the inclined support and the transfer-carrier.

55 7. In a machine of the character described, an elevated inclined support, a plurality of spaced rollers carried thereby, a transfer-carrier pivoted to swing in a substantially vertical plane for movement toward and a way from the inclined support 60 and having spaced supporting elements adapted for movement between the spaced rollers, means to lower the inclined support

with relation to the transfer-carrier, and means to remove the bricks from the transfer-carrier.

8. In a machine of the character described, a supporting structure, an inclined conveyer-trough connected with the supporting structure and provided upon one side with spaced upstanding supporting members, spaced conveyer elements arranged within the conveyer-trough and connected with the spaced upstanding supporting members, a pivoted transfer-carrier carrying spaced supporting elements adapted 75 for movement between the spaced conveyer-elements, and means to remove the brick from the transfer-carrier.

9. In a machine of the character described, a supporting structure, an inclined support connected therewith, a plurality of spaced conveyer elements carried by the inclined support, a swinging transfer-carrier connected with the supporting structure and adapted to be moved to raised and lowered positions and including a plurality of spaced supporting elements to pass between the spaced conveyer elements, a reciprocatory member connected with the lower portion of the supporting structure, means 80 to move the reciprocatory member, a plurality of spaced rods carried by the reciprocatory member and adapted to push the bricks from the transfer-carrier when it is in the lower position, and means to effect a 85 relative vertical movement between the inclined support and the transfer-carrier.

10. In a machine of the character described, an elevated support for receiving a row of bricks, a transfer-carrier adapted for movement in proximity to the elevated support to receive the row of bricks therefrom and for movement away from the transfer-carrier, and means to simultaneously move the bricks from the transfer-carrier.

100 11. In a machine of the character described, a wheeled support adapted to travel upon the curbing as a track, an elevated support connected with the wheeled support to receive a row of brick thereon, a vertically 110 movable transfer-carrier adapted to be shifted to an upper position to receive the row of bricks from the elevated support and to descend to transfer the bricks to a position in proximity to the road-bed, and means 115 to remove the bricks from the transfer-carrier, such means also serving to effect the longitudinal movement of the machine.

In testimony whereof I affix my signature in presence of two witnesses.

NATHANIEL M. LIDDELL.
